Clark Deemert & Co.

UNITED STATES PATENT OFFICE.

OTTO SAGER, OF ROCHESTER, NEW YORK.

HAT-HANGER.

SPECIFICATION forming part of Letters Patent No. 595,736, dated December 21, 1897.

Application filed December 17, 1896. Serial No. 616,016. (No model.)

To all whom it may concern:

Be it known that I, OTTO SAGER, a citizen of the United States, and a resident of Rochester, county of Monroe, and State of New York, have invented certain new and useful Improvements in Hat-Hangers, of which the following is a specification, reference being had to the accompanying drawings, forming a part thereof, in which similar letters and figures of reference indicate corresponding parts.

This invention relates to improvements in hat-hangers; the object thereof being to supply an efficient device for hanging ladies' hats to the backs of theater or other seats located in public places or to the garments of a wearer, if desired. The device is adaptable for permanent attachment inside the hat, and it is capable of carrying an advertisement.

The invention will be hereinafter fully described, and specifically set forth in the annexed claim.

In the accompanying drawings, forming part of this specification, Figure 1 is a perspective view of a lady's hat, showing my improved hanger attached thereto; and Fig. 2 is a perspective view of the hanger, drawn to an exaggerated scale.

In the practice of my invention the hanger or clamp A is composed, preferably, of a single piece of resilient wire, the two ends of which are flattened, as at a, for clamping and contacting with any article to which it is desirable to hang the hat. The lower arm a' of the clamp extends rearwardly to a point 1. It is then brought back to a point 2 and coiled into a spiral spring 3, and then extended rearwardly to a point 4 and coiled into a loop 5, thence forwardly back to the point a, whereby the arm a' of the clamp is formed.

Metallic collars B are preferably attached to the rear of the spring 3 upon each arm of the clamp to strengthen the device, and a shield C, of fabric or other pliable material,

may connect the two rearward extensions of 45 the arms. Upon this shield an advertising announcement c may be placed.

Connected to the loop 5 is a flexible string D, which is secured at its other end to a plate E. This said plate has a sheath e, projected 50 from the center thereof, adapted for receiving and retaining the hanger A when the same is not in use, as clearly illustrated in Fig. 1 of the drawings.

The plate E is provided with apertures e' 55 through the ends thereof for receiving threads, whereby the plate may be securely stitched to the inside of a hat.

In the operation of the device the hanger or clamp is placed within the sheath e, as 60 illustrated in Fig. 1 of the drawings, during the time that the hat is worn. When the hat is removed, the hanger is removed from engagement with the sheath and clamped over any object adapted to hold the hat—for instance, the back of a theater-seat—whereby a lady can conveniently remove her hat in the theater and hang the same up without danger of injury to the hat.

Having thus described my invention, what 70 I claim as new, and desire to secure by Letters Patent, is—

A device for hanging hats and similar articles, comprising the wire clamp A, flattened at both ends, collars B upon the arms of the 75 clamp, a coiled spring located between the arms, in combination with a plate E having a sheath e for clamp A, said plate having a flexible connection to the clamp, substantially as shown and described.

In testimony that I claim the foregoing as my invention I have signed my name, in presence of two witnesses, this 11th day of December, 1896.

OTTO SAGER.
